UNITED STATES PATENT OFFICE.

ISAAC WAGEMAKER, OF GRAND RAPIDS, MICHIGAN.

MACHINE FOR CUTTING, PRINTING, AND STACKING INDEX-CARDS AND THE LIKE.

1,245,645.

Specification of Letters Patent.

Patented Nov. 6, 1917.

Application filed October 25, 1915. Serial No. 57,742.

To all whom it may concern:

Be it known that I, ISAAC WAGEMAKER, a citizen of the United States of America, residing at Grand Rapids, in the county of 5 Kent and State of Michigan, have invented certain new and useful Improvements in Machines for Cutting, Printing, and Stacking Index-Cards or the like; and I do hereby declaré the following to be a full, clear, 0 and exact description of the invention, such as will enable others skilled in the art to which it appertains to make and use the same.

This invention relates to mechanism for 5 automatically cutting, printing and stacking index cards which are to be located within any suitable receptacle, the cards being used as separators and indicators in filing papers or the like. Heretofore it has been necessary 0 in the manufacture of packs of index cards to cut a number of cards of the same kind, print them with the same character and after this operation has been completed with respect to all of the cards necessary to make a 5 complete pack, the cards are sorted and gathered together in proper relation to each other so that a plurality of complete filing packs are produced beginning with the first 0 character of the series and ending with the last and having index tabs in staggered relation one behind the other. While packs of 0 index cards could be and have been obtained in this manner, the process is long and comparatively costly.

It is the primary object and purpose of 5 my invention to provide a mechanism such that a plurality of plain square-cut cards may be fed into it and during the course of their progress through the mechanism be 0 cut to leave an index tab at one edge and have an indicating character printed on this tab, each card being cut and printed differently from the cards preceding or following so that when delivered from the mechanism 5 a plurality of cards having index tabs properly cut and printed and with the tabs in proper staggered relation to each other may be obtained, the pack being fully completed and stacked, ready for insertion in its receptacle. A further object of the invention resides in the provision of mechanism for cutting the tabs so that they will locate in 0 staggered relation one behind the other and in providing printing mechanism which will 5 operate step by step with the cutting of the

cards so as to print the tabs with the characters of the alphabet or with any other desired characters consecutively and in reverse order. A further object of the invention consists in the provision of an auxiliary or 60 additional printing mechanism by means of which the body of the cards may be imprinted with any suitable advertisement or the like, said mechanism including also means for causing this imprint on each card to be 65 located in exactly the same relative position with respect to the card. Still further objects of the invention consist in the provision of novel feeding mechanism for feeding the plain cards one at a time to the machine; 70 in the provision of novel regulator and card stopping devices for regulating the position of the card and holding it in said position during the operation of cutting and also during the operation of printing the index 75 tabs left after the cutting operation is completed; in the provision of novel inking mechanisms for transferring ink to the type; and in the provision of many new and useful features of adjustment for the machine 80 whereby it may be utilized to cut and print index cards of all sizes with varying widths of index tabs, with different numbers of tabs in staggered relation and with the tabs located at any desired position with respect to 85 the complete pack of cards.

To accomplish these ends as well as many other new and useful objects and purposes that have not been specifically enumerated but which will appear as the description 90 progresses, I have embodied my invention in a mechanism disclosed in the accompanying drawings, in which;

Figure 1 is a view from one side of the central or cutting and printing section of 95 the machine.

Fig. 2 is a plan view of the construction shown in Fig. 1.

Fig. 3 is a view from the opposite side of the machine shown in Fig. 1 and also showing at one end a part of the feeding mechanism for feeding the cards into the central section of the machine.

Fig. 4 is a plan view of the feeding device.

Fig. 5 is a front elevation thereof. 105

Fig. 6 is a side elevation.

Fig. 7 shows in plan and front elevation a detail of the feeder.

Fig. 8 is a partial plan view of the rear portion of the machine showing the aux- 110

iliary printing attachment thereon which prints the advertisement on the cards.

Fig. 8^a is a fragmentary side elevation of a detail of the construction.

5 Fig. 9 is a vertical section taken on the line 9—9 of Fig. 8.

Fig. 10 is a side elevation of the rear portion of the machine taken from the same side as Fig. 1.

10 Fig. 11 is a similar view taken from the opposite side of the machine, Figs. 10 and 11 illustrating particularly side elevations of the auxiliary printing device.

Figs. 12 and 13 are details of construction 15 pertaining to the operation of the inking rollers in conjunction with this auxiliary printing device.

Fig. 14 is a perspective view of the inking mechanism for the printing mechanism that 20 prints the characters on the index tabs.

Fig. 15 is a plan view thereof.

Figs. 16, 17 and 18 show respectively a plan and front and side elevations of the 25 vertically movable frame which carries the inking roller in this inking mechanism.

Figs. 19 and 20 are side elevations of this inking device taken from the opposite sides thereof.

Fig. 21 is a vertical section taken through 30 the inking device.

Fig. 22 is a perspective view of the regulating and stop mechanism for properly positioning the cards for cutting and printing.

Fig. 23 is a perspective view of the cam 35 which controls this mechanism.

Fig. 24 is an end elevation with parts shown in section of the stop mechanism with adjacent parts of the tab printing ram.

Fig. 25 is a front elevation of the ram 40 which presses the index tab against the type in the operation of printing.

Fig. 26 is a front elevation of the cutting mechanism for cutting index tabs.

Fig. 27 is a side elevation thereof, parts 45 of the supporting frame being shown in section.

Fig. 28 shows in plan and in front and end elevation the lower cutting knife of the mechanism.

50 Fig. 29 shows, similarly, the upper cutting knife.

Fig. 30 is a perspective view of a fragmentary portion of the machine illustrating the method of moving the type ring step by 55 step as the machine operates.

Fig. 31 is an elevation illustrating the cam and connecting mechanism for operating the type ring.

Fig. 32 illustrates in perspective the 60 means for operating the feeding mechanism and also the particular mechanism for rendering said feeding device inoperative under certain conditions.

Fig. 33 is a perspective view of a fragment 65 of the mechanism showing the relation

tion and connection of the timing mechanism to the printing ram and the type ring, and the means incorporated therewith for periodically rendering them inoperative.

Fig. 34 is a plan view of the timing disk 7 and ratchet wheels.

Fig. 35 is an end elevation thereof, and Fig. 36 in a vertical section on line 36—36 of Fig. 34.

Fig. 37 is a plan view of a detail of construction of a guide between which and the printing ram the type wheel passes and at which point the printing of the index tabs occurs.

Fig. 38 is a side elevation thereof.

Fig. 39 is a front elevation with a part shown in section.

Fig. 40 is a plan view of one of the pressure rollers underneath which the cards pass in the machine.

Fig. 41 is a side elevation thereof.

Fig. 42 is an end elevation with a part shown in section.

Fig. 43 is a plan view of the timing mechanism showing the relation of the parts for controlling the feeding and printing devices with respect to the disk of said mechanism.

Fig. 44 is a view taken from beneath a type wheel.

Fig. 45 is a side elevation of the type wheel.

Figs. 46 and 47 are, respectively, transverse sections taken on the lines 46—46 and 47—47 of Fig. 44.

Figs. 48 and 49 illustrate in side elevation and plan, respectively, one of the types utilized in printing with two colors on the index tabs.

Fig. 50 is a plan view of a type ring showing the association of said ring with cams on the machine for controlling the position of the type in inking and printing when two colors are to be used; and

Fig. 51 is a front elevation of a pack of cards cut, printed and stacked by my machine.

Fig. 52 is an enlarged plan, partly in section, showing a detail of the detachable feature of the feeding mechanism.

Like reference characters refer to like parts throughout the several views of the drawings.

In the construction a suitable supporting structure is provided including vertical posts 1 located at the corners of the supporting frame which is rectangular in outline, the posts at one side of the frame being connected at their upper ends by a horizontal beam 2. Similarly the posts at the opposite side of the machine are connected by an upper horizontal beam 3, and at each end cross beams 4 connect the upper ends of the posts. Below the beams 2 and 3, respectively, additional horizontal beams 5 and 6 are provided, to brace the posts and

serve as supports for various portions of the mechanism as will hereinafter appear.

A shaft 7 mounted in suitable journals 8 on the beams 5 and 6 is located transversely of the frame and at one end carries a drive wheel 9 which is driven from any suitable source of power by a belt 10. Shaft 7 is the main driving shaft of the entire mechanism and all parts of the mechanism are driven thereby. A sprocket wheel 11 is secured to the shaft driving an endless sprocket chain 12 which passes around a sprocket wheel 13 fixed on the end of a shaft 14 at one end of the central section as shown in Figs. 2 and 3, shaft 14 being supported by brackets 15 and 16 secured to the end posts 1. On the shaft 14 is fixed a sprocket wheel 17 driving a sprocket chain 18 which passes around a sprocket wheel 19 attached to a shaft 20 located almost directly beneath shaft 14 and supported by suitable brackets connected to the frame of the machine. A wheel 21 is fixed to the front end of shaft 20 around which passes an endless belt 22. A table 23 rigidly connected to what may be termed the front side of the supporting frame projects in front of the frame and belt 22 leads from the wheel 21 over a pulley 24 at the front end of the table, the belt thereafter passing the full length of the table and around a pulley 25 fixed to a short shaft 26 supported by brackets 27 at the rear end of the table, and then passing downwardly under the table around an idle pulley 28 carried by the link 29 which in turn is supported by bracket 30 attached to the underside of the table and thence forward around an idle pulley 31 similarly supported by a bracket 32 attached underneath the table, pulley 31 being located adjacent to the drive wheel 21 heretofore described. The link 29 is pivotally connected to the bracket 30 and may be used to give a suitable tension to belt 22. A short distance in front of belt 22 a similar belt 33 is positioned leading around a pulley 34 on the shaft 14, passing thence lengthwise of the table around a pulley 35 on the shaft 26 and thence under the table over an idle pulley 36, supported beneath the table, and the idle pulley 37 carried at the end of the link 38 which is pivotally mounted on the bracket 39 as shown in Fig. 1, this belt being given any proper or desired tension through the medium of the link 38 as will be apparent. A plurality of bracket supports 40 are secured to the machine a short distance back of the table 23, carrying a rod 41 which is located directly above the belt 22. At a number of positions throughout the length of the rod, pairs of clips 42 are located which are adjustably fixed to the rod by means of a pin 43 and thumb nut 44 illustrated particularly in Figs. 40 and 42. A rod 45 is connected to one of the clips 42 and passes

through the other toward the front of the machine. On each rod a link 46 is pivotally mounted. A collar 47 is carried at the forward end of each rod 45 being provided with notches 48 in its front face in which diametrically opposed pins 49 fixed at the end of rod 45, seat. A torsion spring 50 passes around each rod 45 and is located between and secured at its ends to link 46 and collar 47 associated therewith. By forcing the collar 47 inwardly and turning it in the proper direction the tension of the spring 50 may be increased, the effect of it being to force the end of link 46 in a downward direction. At the end of each link 46 a bar 51 is pivotally secured, said bar carrying at each end short shafts on which rollers 52, preferably having rubber surfaces, are mounted. These rollers are forced by the spring tension of springs 50 against the belt 22. Accordingly, cards entered at the front end of the table between rollers 52 and belt 22 are carried with the belt when no obstruction is offered to their travel, but the positive movement is not so pronounced that injury will occur to a card if it is stopped at any portion of its travel along the belt. The belt 33 is of value when wide cards are introduced into the mechanism, they traveling in unison with the belt 22 whereby the wider cards at their outer edges resting on the belt 33 are carried more uniformly than if the single belt 22 was used.

The feeding mechanism for introducing the cards into the central section of the machine is located at the front end of said section. In the construction of the feeding mechanism a horizontal plate 53 is provided and supported at proper height by posts 54 which may be connected by any suitable cross braces 55. Adjacent the forward end of the central section of the machine a pair of spaced apart members 56 and 57 are secured to the base 53 between and in which are mounted upper and lower shafts 58 carrying short rollers 59 which are in contact with each other in pairs as shown in Fig. 5. A series of small pinions 60 secured to shafts 14 and 58 drive the rollers so that any card passed to the rollers is gripped and carried to the belt 22. The tension of the rollers is adjusted by means of the set screws 61 so that the pressure of the upper rollers on the lower one may be regulated as desired.

Positioned in contact with and secured to the inner sides of the members 56 and 57 are a pair of supports 62 between which is located an inclined member 63 which supports an adjustable finger 64, the adjustment being effected by the slotted connection illustrated at 65. The finger 64 may be moved up or down to conform to various thicknesses of cards that pass between its lower end and the base 53 on which they rest. A side guide 66 is adjustably con-

nected to the base 53 by means of brackets 66^a at the rear side of the table and on it is mounted a slidable gage 67 which is movable to any position on the guide for any 5 length of card placed on the base 53. The inclination of the guide 67 is the same or substantially the same as that of the finger 64 so that when a pack of cards is placed between it and the finger the lowermost card 10 is always located slightly in front of the card next above. Adjacent the forward edge of the base 53 an adjustable side guide 68 is mounted, the adjustment being effected by means of rods 69 attached to the side and 15 passing through suitable posts which carry the set crews 70 whereby the side guide may be fixed in any desired position for any width of card. These rods may also serve as a support to carry a work table 71 on 20 which the plain cards may be placed for convenience adjacent the feeding device.

In the base 53 a pair of spaced apart slots 72 are cut which extend lengthwise of the base and in which are mounted bars 73 connected together by a transverse member 74 25 that passes underneath the base. A lever 75 is pivotally connected to the member 74 and is pivotally mounted between its ends on a support 76 connected to the base 53. A bar 30 77 is pivotally and adjustably connected to the end of the lever 75, slot 78 being formed in the lever to permit the adjustment of the end of bar 77. Bar 77 extends rearwardly and at its rear end is connected to the under- 35 side of a block 79 through which passes a rod 80 loosely carried directly back of the block by a bracket 81 secured to the front upper cross member 4 of the main frame. At its rear end rod 80 is pivotally connected 40 to a lever 82 which is pivotally mounted between its ends to a suitable support 82^a and which at its lower end engages in a groove 83 formed in the face of the disk 84 fixed on the drive shaft 7. Groove 83 is 45 of such formation that with each revolution of the shaft the lever 82 is oscillated about its pivot, in this manner giving to the rod 80, the block 79 thereon and bar 77 attached to the block a single complete reciprocation 50 so that the bars 73, with each revolution of the drive shaft 7, move back and forth once. Bars 73 are provided with dove-tail grooves on their upper sides and a cross bar 85 is mounted between bars 73 and adjustably 55 connected thereto so that it can be moved back and forth in these grooves. A rib 86 is secured to the upper side of the bar 85, its edge projecting the thickness of one card above the upper surface of the bar. It will 60 be noted that bar 85 tapers substantially to a point at its rear edge so that with each revolution of the shaft 7 as it moves forward it passes underneath the pack of plain cards placed on the base 53, the member 86 en- 65 gaging with the lowermost card in the pack

and carrying it to the rollers 59 whereupon it is gripped and fed on to the belt 22 and carried to the rear under the rollers 52.

There is also mounted on the table 23 a 70 guide plate 87 which may be adjusted back and forth in ways 88 formed in the table and held in any desired position by tightening the set screws 89. With narrow cards the belt 33 is removed and the guide plate is moved as closely as necessary to the belt 22. 75

A distance back of the front end of the central section of the machine a bracket 90 is secured to and projects upwardly from horizontal beam 3 at its upper end being provided with a bearing 91 receiving one 80 end of a shaft 92. The opposite end of this shaft is received within a bearing adjustably carried between rigid guides 93 which are supported by and between two upright spaced apart standards 94 supported by the 85 horizontal beam 2 and an auxiliary beam 96 located back of beam 2 and at the upper ends of posts 97 and 98. These auxiliary supporting structures are necessitated on account of the extra weight and strain to 90 which the mechanism is subjected at these points. At their lower ends each of the upright supports 94 are formed with a forwardly projecting portion 99 adapted to carry horizontal members 100, each of said 95 members being independent of the other and having a dove-tail projection 100^a on its underside seating in a groove of similar formation in the upper side of the part 99. The members 100 may be slidably adjusted 100 to any desired position and retained in such position by the set screws 101. On the upper side of each of the members 100 a knife 102 is secured by means of screws or other suitable permanent connecting devices, the 105 rear side of the knives lying in a straight line parallel to the length of the machine except at one end where each is widened and formed as shown at 103.

The forward end of the shaft 92 carries a 110 cam 104 in the front face of which is cut a groove 105 of such formation that an inner cam is made concentric with the shaft through an arc of substantially 300 degrees but having a projection as indicated at 115 104^a for the remainder of the circumference. A member 106 is suspended on a roller in groove 105 and carries at its lower end a head 107 on the underside of which is mounted a pair of supporting members 108, 120 each having a dove-tail upper rib 108^a slidably received within a similarly formed groove in the underside of member 107, so that parts 108 are adjustable to different positions being held in any desired position 125 by set screws 109. Members 108 on their undersides carry knives 110 which for the greater portion of their length are comparatively wide but which at one end narrow down as shown at 111 leaving a recess 111^a 130

of substantially the same formation as the widened portion or shoulder 103 on the knives 102 heretofore described. The knives are so positioned with respect to each other 5 that knives 110 pass immediately behind the knives 102 and any cards positioned between them will, when the upper knives are lowered, have portions sheared off leaving a projecting tab at the points where portions 10 103 pass within the recesses 111^a of the upper knives 110. The length of a tab may be regulated by adjusting the members 100 and 108 back and forth on their respective supports 99 and 107 as will be readily understood. As shaft 92 is rotated, each revolution thereof raises and lowers the upper knives once. Stripping bar 112 is mounted immediately in front of the upper knives 110 and is normally actuated by springs 113 15 to a lower position. These springs are received around pins which carry the stripping bar, the pins being slidably mounted in guides 114 attached on the front face of the head 107. On the downward movement of 20 the upper head, as the cutting operation takes place, stripping bar 112 is forced against the lower knives 102 and springs 113 compressed. On the upward movement of the head 25 the stripping bar 112 takes its normal position and forces the card which has been cut away from the upper knives, in this manner insuring against any tendency of the card to lift with the upward movement of the head. Also the stripping bar as it 30 is pressed upon the cards during the operation of cutting serves to hold the cards firmly against any movement which might occur otherwise. As a means for guiding and steadyng the movement of the head 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

It is essential that the cards as they come 65 to the cutting dies reach the dies before the downward movement of the head 107 takes place and also that they be stopped at proper positions so the tabs shall be formed at exactly the right place with respect to the 70 bodies of the cards. Mechanism for effecting this is shown in enlarged detail in Figs. 22, 23 and 24. On the end of the drive shaft 7 a pinion 125 is secured which meshes with a gear 126 attached to the short shaft 127, 75 this shaft also having fixed thereon a composite cam denoted as a whole by reference character 128. Shaft 127 projects forwardly from a plate 129 which is mounted between upper and lower ways 130^a formed 80 on the face of the plate 130 secured to the frame of the machine. Plate 129 may be adjusted back and forth with respect to the plate 130 and held in any desired position by means of set screws 131 and 131^a. In 85 the construction as shown, the mechanism is of such character that the tabs on the cards are cut substantially one-fifth of the width of the cards and when in proper staggered relation one behind the other, five of 90 such tabs will make the full width of a card. With the machine fixed to cut cards in this manner the relation of the pinion 125 to the gear 126 is as 1 to 5. However, the machine is not limited to this one kind of card and 95 different relations of gears and different composite cams 128 may be used for different conditions; and the gear 126^a shown in Fig. 24 in front of gear 126 has a less number of teeth than gear 126 and may be 100 made to mesh with a pinion having a greater number of teeth than the pinion 125 so that a relation of 1 to 1, if desired, may be obtained. Also a larger pinion may be placed on the shaft 7 to drive gear 126 making a 105 relation of 1 to 4, 1 to 3, or 1 to 2, the adjustability of the plate 129 permitting such interchange of parts.

In the composite cam shown in Fig. 23, 110 five disks 132 are provided each having a single projection 133 at a portion of its circumference. The projections occur in spaced apart relation and not at the same position with respect to each disk. The disks 132 are separated by intermediate 115 disks which are formed with consecutive projections and depressions 134 and 135, there being five projections and depressions in the circumference of each disk in the drawings as shown. The lengths of the depressions and of the projections vary with different disks.

On a shaft 136 and projecting forwardly from plate 129 are pivotally mounted a plurality of levers 137 having arms extending 125 upwardly and downwardly from the shaft, each of the lower arms carrying a roller 138 which bears against a disk 132. There are

five of these arms in the construction shown and each disk has a roller 138 bearing against it. Each arm at its upper end is forked as shown at 139, the fork passing between a pair of collars 140 attached to each rod 141. Rods 141 are of varying lengths and to each, at each end, is adjustably connected a block 142 which may be set at any desired position by means of a set screw 143. On the underside of the table 123 and closely adjacent its rear edge the bar 144 is secured by means of screws or other permanent connections and this bar carries ten blocks 145 which through the medium of fastening blocks 146 and set screws 147 may be adjusted to and fixed at various positions along the length of the bar. Five of the blocks are in front of the composite cam and five of them are back of the cam. Short shafts 148 extend, one through each of the blocks, and at their front ends are equipped with downwardly extending arms 149 which pivotally connect with the blocks 142 heretofore described. At its rear end each shaft 148 carries a cam 150 having an inclined face against which bears the inclined end 151 of a rod 152 positioned vertically and extending through integral projections 153 formed on the blocks 145. Coil springs 154 interposed between the projections and the lower ends 151 of the rods normally keep the lower ends of the rods in close contact with the cams 150. Rods 152 extend upwardly closely adjacent the rear side of the table 23, each being provided at its upper end with a head 155. The heads of the forward rods pass between the table 23 and the lower stationary knives 102 and in their normal position said heads lie slightly below the upper surfaces of the knives and the upper surface of the table 23 as shown in Fig. 22. The heads on the rods 152 back of the cam 128 pass between the table and an angle member 156 as fully shown in Fig. 22, normally lying slightly below the upper surfaces thereof. It will be evident that with the revolution of the cam 128, as the projections 133 of disks 132 serve to actuate levers 137, a rod 141 associated with the lever actuated is moved forwardly and serves to elevate a head 155 at the front and at the rear, above the upper surface of the table. These upward movements of the heads take place consecutively and in the course of five revolutions of the drive shaft 7, with the construction as illustrated in the drawings, all of the heads 155 will have been elevated as described and with each revolution of the shaft one head in front and one head behind is elevated. The elevation of the heads occur progressively from the rear toward the front and a card that is being carried along by the belts 22 and 33 is stopped when it strikes an elevated head. The mechanism is so related

and timed that this stoppage occurs with any of the front bank of heads immediately before the downward movement of the cutting knives takes place. Also this stoppage occurs for a length of time sufficient to permit the cutting of the card and return of the cutting knives after which the head 155 goes to its normal position permitting the card to be carried farther along. The rear bank of heads serves to stop the cards and hold them in position for the operation of printing the tabs, the mechanism for which will be later described. It will be noted that the rear stop of the front bank of stops and the rear stop of the rear bank of stops do not elevate simultaneously but that the stops of the two banks are so connected that when a forward stop is elevated there is simultaneously elevated a stop in the rear bank which is one position away from the stop that is elevated in the front bank. This is necessary on account of the fact that a card moves from the position at which it is cut to the position at which its tab is printed while the drive shaft is making one complete revolution and the printing of the tab must take place one cycle of the machine after the cutting of that particular tab has taken place. Accordingly the relation of the stops in the front and rear banks and the connection thereof is as illustrated in Fig. 22 to allow for this complete cycle of the machine occurring between the cutting and the printing of a particular tab. It will be clear that by reason of the consecutive elevation of stops occupying different relative positions with respect to the knives, the cards are stopped at different relative positions and the tabs which are left thereon are arranged correspondingly in different positions with respect to the bodies of the cards, and that with consecutive elevation of the heads, the tabs of cards following one after the other are moved over one step with respect to the tab which has been left on the preceding cards.

A short shaft 157 projects forwardly from the plate 129 and has a member 158 pivotally mounted thereon from which a plate 159 extends downwardly on which is mounted a downwardly projecting arm 160 carrying at its end a roller 161 which may be adjusted back and forth on the arm to any desired position along the slot 161^a. The arm also may be adjusted to any desired position on the plate 159 in a slot 162 formed therein to permit said adjustment. In this manner the roller 161 may be made to bear against any of the disks positioned between the disks 132. An arm 163 projects upwardly from and is secured to the shaft 157 having pivotal connection to the rear end of bar 164, the front end of which passes through an ear 165 formed on the downwardly extending arm 166 of a bell crank 130

lever which is mounted at 167 on the beam 2. On the arm 166 a dog 168 is mounted adapted to engage in any of the plurality of notches 169 formed adjacent the end of bar 164. The other arm of the bell crank lever 170 extends forwardly in a horizontal direction and at its end is connected to an upright rod 171 which terminates in an upright bar 172, the upper end of which normally lies slightly below with the upper surface of the table 23. With the revolution of the composite cam, and with roller 161 alternately seating in a depression 135 and riding over a projection 134, the bar 172 is raised and lowered and with a complete revolution of the cam shown in Figs. 22 and 23, bar 172 raises and lowers five times; or with every elevation of a stop 155 a corresponding elevation of the bar 172 has taken place. This elevation of the bar 172 takes place in such time as to stop a card fed into the machine, hold it for a period of time and then release it for further travel such that the head 155 which is to later stop it will have had time to be elevated in position. This regulating device is essential as otherwise, many times, the cards would reach the position of a head 155 before the head was raised and pass on without being acted upon by the cutting mechanism. Also on account of the different positioning of the stops 155 it is essential that each card be stopped and properly released by the regulating bar 172 so that the time when any card shall reach its stopping head 155 after the head has been raised shall be exactly equal to that of any other head. Accordingly the projections and depressions 134 and 135 are properly formed and arranged and timed so that this action will take place. Furthermore with cards of varying sizes a regulating device of this character is necessary in order to properly guide and govern their travel through the cutting mechanism, it of course being understood that many different composite cams 128 may be used for varying conditions respecting sizes of cards and number of tabs.

The cutting and regulating mechanism has been described with respect to a cam having five disks between which are mounted five other disks, each of which has five projections and five depressions. It is of course apparent that a cam with three or 50 four disks between which are mounted other disks having three and four projections and depressions respectively may be used in which case two of the levers 137 and the mechanism attached thereto will be rendered 55 inoperative. The cards fed into the machine and cut, accordingly, will be cut on the basis of three and four tabs for the width of a card instead of five as described. To 60 keep the levers 137 in contact with disks 65 132 leaf springs 173 are used, one bearing

against each lever as shown in Fig. 1. These springs are carried by a member 174 which is adjustably mounted on the plate 129 so that the tension of the spring may be increased or diminished at will.

A plate 175 is mounted on the frame of the machine back of the rear bank of stop rods 152 being substantially circular in outline. At its outer edges and on its upper side a plurality of brackets 176 are mounted, 75 each carrying a pair of spaced apart horizontal rollers 177 and a vertical roller 178. A type ring 179 is mounted on the rollers 177, its outer circumference lying within the rollers 178. The ordinary type rings with 80 which but one color of letter is printed are grooved on their undersides as shown in Fig. 46 carrying therein a block 180 from which projects the type characters 181. Mounted on the drive shaft 7 is a disk 183 in 85 the front face of which is cut a groove 184 of the outline best shown in Fig. 31. A lever 185 at its lower end carries a pin projecting into groove 184, the lever being pivotally mounted on a stud 186 carried by a plate 90 187. The stud is adjustable back and forth to any desired position in a slot 188 formed in the plate. The plate in turn is adjustably mounted upon a support 189, studs 190 projecting therefrom through slots 191 in the 95 plate so as to permit a vertical adjustment of the plate with respect to the support. A guard bar 192 is also provided passing in front of the lever 185 and attached to forwardly projecting portions of the support 100 189 as shown.

Lever 185 at its upper end carries a bar 193 which is bent to the rear and from which projects a stud 194 adjustably mounted thereon. A bar 195 lying horizontally with its rear end just above the pins 182 is pivotally mounted on the vertical pin 196 for oscillatory movements in a horizontal plane. At its rear end an extension 197 is pivotally mounted on a horizontal axis and in this extension a slot 198 is formed through which the pin 194 carried by bar 193 projects. The pivotal connection of the extension 197 is provided to permit the disengagement thereof from the bar 193 whenever desired. Bar 195 at its rear end carries a pivotally mounted push bar 199 which has its free end bent downwardly so as to engage behind the pins 182. The support 200 for bar 195 is of such height that the push bar can move freely over the pins 182 in one direction the same as a pawl rides over a ratchet but as it is moved in the other direction it engages a pin and moves the type ring forward one step; that is with each revolution of the drive shaft 7 the type ring is moved one step when the parts are in the position shown in Fig. 30. Attached to the free end of the member 199 is a member 201 which projects forwardly and has the forward end turned 130

down as shown, the use of which will later appear.

Directly back of the table 23 a base 202 is secured to the plate 175 from which projects a guide rib 203 slidably carrying a support 204 which may be fixed at any desired position on the guide rib by means of a screw operated by the hand wheel 205 as shown in Fig. 38. Between the ears 206 of support 204 a head 207 is pivotally mounted which may be adjusted within limits by the adjusting screw 208 bearing against support 204. A plate 209 is suspended by rods 210 below the head 207 and in front of the support 204 and is normally forced downwardly by a coil spring 211 located within a recess in the head, the tension of which may be increased or diminished by operation of the screw plug 212. The type wheel 20 passes underneath the plate 209, pins 182 passing between the spaced apart projections 209^a fixed to said plate while the underside of the wheel is supported by means of a bracket 213 terminating in a curved rest 214. The movement of the support 204 is necessary when a type ring is to be removed or replaced by one of different character.

Located directly beneath the type ring 30 and the plate 209 is a head 215 covered by a fiber covering 215^a, the head being mounted at the upper end of a post or ram 216 and movable up and down between clips 217, and a supporting plate 218 to which the 35 clips are attached. Supporting plate 218 is rigidly secured to the frame of the machine. An angle plate 219 is fastened to plate 218 and through the forwardly projecting leg thereof the rod 216^a forming a part of the 40 post passes. A strong coil spring 220 is interposed between the angle plate 219 and a collar 221 which is secured to rod 216^a, the tendency of the spring being to force the post and its attached head downwardly. At 45 the lower end of the post and below the lower clip 217 a U-shaped member 222 is pivotally suspended having inclined lower edges 223. A disk 224 bearing a roller 225 at one portion of its periphery is fixed to 50 the drive shaft 7 and with each revolution of the shaft the roller 225 bears against the inclined end of member 222 serving to elevate the post or ram and its head 215. The rear stops 155 operate to stop the cards with 55 their projecting tabs directly below the type ring which has been moved to bring a character directly above the tab and with the upward movement of the post 216 the tab is forced against the type and the character 60 imprinted thereon. With cards of different material and thickness the pressure to obtain a proper imprint will vary and this may be regulated by the screw plug 212. I have also provided an additional means of 65 adjustment in the printing ram, it being

noted that the rod 216^a is threaded at one end with the right hand screw threads and at the other end with left hand threads so that by turning it the ram may be shortened or lengthened as desired. Furthermore 70 plate 175 and the mechanism attached thereto is adjustable slightly back and forth with respect to the frame of the machine being retained by guides 226. The adjustment is effected by a screw 227 operated by hand wheel 228 as shown in Figs. 2 and 3. This adjustment will ordinarily be very slight but with tabs of different sizes is necessary for the best appearance and effect.

In this connection it may be stated that 80 the printing of the cards is in reverse order beginning with the last characters of a card pack and ending with the first character for the pack, so that when a pack of cards has passed through and fallen in the receptacle 85 therefor the first card printed will be at the bottom of the pack while the last card will be at the top, thus forming a complete pack ready to be placed in a filing drawer or other receptacle.

The type is inked previous to the pressure of the tab against it at a point a distance about the arc of 90 degrees from the point of printing. In the construction of the inking device, a base 229 is secured to the rear 95 end member 4 and from the base project sides 230. A partition 231 lying parallel to the sides divides the casing thus formed into two compartments. Inclined members 232 are interposed between sides 230 and the partition upon which the ink is placed, it sliding by gravity against rollers 233. In one of the compartments black ink is used and in the other ink of any desired color may be used. Rollers 233 are mounted on a 100 shaft 234 and the ink that sticks to the rollers is spread thereon and the excess scraped away by a scraper 235 mounted on a sliding block 236 which may be moved back and forth by means of the screw 237 which has an operating head 237^a on the outside of the end 238 of the casing. A shaft 240 passes through and is rotatably mounted in the sides 230 and on it are mounted rollers 241. Between the sides of the casing a carriage 105 having sides 242 is positioned, these sides having openings 243 permitting the passage of shaft 240 and the vertical movement of the carriage as hereafter described. The upper ends of sides 242 are secured together 110 by a cross rod 244. At each side of the cross rod pairs of rollers 245 are positioned being mounted on shafts 246 which at their ends are rotatably mounted in bearings 247 received within notches in the sides 242. 115 Bearings 247 carry screws 248, the lower ends of which bear against the upper ends of posts 249 secured to the sides of the carriage as indicated in Figs. 17 and 18. By 120 operating the adjusting screws the rollers 125 130

may be raised or lowered as desired and when in position may be secured by set screws 250. In the lowermost position of the carriage the rollers 245 bear against rollers 240. Another pair of rollers 251 are mounted on a shaft 252 which is removably inserted and retained in the slots 253 formed at one edge of the sides 242, this roller in its lowermost position bearing against the rollers 233 but on elevation of the carriage contacting with the rollers 241.

5 A cross bar 254 connects the sides 242 of the carriage at their lower edges. This bar rests on the end of a lever 255 pivoted between ears 256 on the block 257 as shown in Fig. 21. A rod 258 is rotatably supported by and between sides 230 of the casing at one edge as shown and between said sides carries an arm 259, the end of which bears 10 against the free end of lever 255. A second arm 260 is connected to the shaft 258 and a link 261 pivotally connects this arm with a lever 262 pivotally mounted at 263 on the outside of one side of the casing. At its 15 free end and on its underside lever 262 carries a block 264 which is pivotally mounted on a pin 265 extending upwardly through the end of lever 262, a torsion spring 266 wound around this pin and secured at one 20 end thereto and at the other end to the lever 262 tending normally to keep the block in position underneath the end of the lever. A pin 267 projects downwardly from the block 264.

25 On the drive shaft 7 a roller 268 is fixed to one side of which a pulley 269 is secured around which passes an endless rope or other flexible drive 270 which, passing around idle pulleys 271 is guided and its 30 direction changed so that it may pass around and drive the pulley 272 fixed on the end of shaft 240. Accordingly it will be evident that when the machine is operated shaft 240 and the rollers 241 thereon are 35 continuously moving. In the periphery of roller 268 a groove 273 is cut which at one point changes direction to form a cam 274 as indicated in Fig. 14. A lever 275 is pivotally mounted between its ends to the frame 40 of the machine and has a pin extending into the slot 273 whereby with each revolution of roller 268 the lever is oscillated back and forth once about its pivot and over the face of the cam. This lever extends rearwardly and upwardly and has pivotal connection to a bar 276 slidably mounted at the side 230 of the casing directly below the lever 262. The bar is provided with slots 278 through which pins 277 extend for holding 45 it on the side of the casing and permitting the sliding movement. An arm 279 is loosely connected to the shaft 234 and at its lower end is connected by a pin and slot connection as shown at 280 to the bar 276. Arm 50 279 carries a pawl 281 which is spring actu-

ated to engage with ratchet wheel 282 secured on the end of the shaft 234. It will be apparent that with each revolution of the drive shaft of a consequent reciprocation of the bar 276 a partial rotation of shaft 234 70 and of the rollers 233 attached thereto will take place. Secured to the bar 276 directly below lever 262 is a bar 283 on which is fixed a block 284 having a downward incline 285 at one end and with an inward incline 286 75 at the opposite end. As the bar 276 moves to the right (see Fig. 19) pin 267 rides up the incline 285 depressing the end of lever 262 and similarly the end of arm 259 serving thereby to elevate the carriage containing 80 the inking rollers by reason of the movement imparted to lever 255. This movement will take place just as the rollers 245 come beneath a type character on the type ring, and ink which has been transferred to them 85 from roller 233 by rollers 241 and 251 will be transferred to the type so that it can in turn be impressed upon the index tabs. The elevation of the carriage 242 and the rollers mounted thereon occurs but momentarily or 90 until the block 284 has traversed to a point such that the pin 267 drops down behind the block. On the return movement of bar 276, pin 267 and the attached block 284 are thrown outwardly and ride along the 95 outer face of incline 286 and block 284 until they reach the position indicated in Fig. 19 whereupon the spring 266 will throw the block back with pin 267 directly above the incline 285. At the opposite end of shaft 100 240 a wheel 287 is secured having a groove 288 therein which runs slightly at an incline as shown in Fig. 15 and in this groove, a pin 289, projecting from a bracket that is firmly secured to the side of the casing, is 105 inserted so that with the revolution of shaft 240 the pin bearing against the inclined sides of the groove 288 serve to give a continuous oscillating endwise movement to shaft 240 causing the rollers 241 to move 110 back and forth with respect to the rollers 245 and transfer the ink smoothly and evenly thereto. A casting 290 is pivotally mounted at 291 to the plate 175 and has a part extending over the type ring immediately 115 above the inking roller. By means of a screw 292 this casting may be adjusted so that the rollers 293 carried by it may bear with proper pressure against the upper side of the type ring. A member 294 is pivotally mounted between brackets 295 fixed to the main frame of the machine, its upper end being bent inwardly over the end of the casting 290 and carrying a pin spring operated by the spring 296 which passes 120 through the end of member 294 and into the casting, locking the casting from any movement when the inking rollers are elevated and pressed against the type on the underside of the type ring. When the ring is to 125 130

be disengaged from the machine parts 294 and 290 may be turned about their pivots so as not to obstruct the removal of the ring.

Ordinarily the tabs are printed in but one color of ink but at times it is desirable that more than one color be used. Adjacent the inking mechanism is mounted a plate 297 having a groove 298 in its upper face. The type rings used when two colors of ink are to be printed on the index tabs are of modified construction including not only the stationary type 181 which prints the black characters but also type 299 mounted upon blocks 300 which are attached to slides 301 movably mounted in guides 302 secured on the underside of the type ring 179. A pin 303 projects downwardly from each slide and in the movement of the type ring, when a pin 303 enters the groove 298, the type 299 associated therewith is drawn outwardly and held in proper position to receive ink from the inner pair of rolls 145 which may be supplied with ink of different color from that supplied to the outer rolls and which ink the relatively stationary type 181. Type 299 is mounted so as to be positioned closely adjacent the permanently fixed type characters and as the type ring approaches the place of printing a cam 304, formed as the arc of a circle and mounted in guides 305 attached to the support 204 and projected in front thereof by springs 306, engages with the pins 303 forcing the slide 301 and the attached type 299 into position so that when the printing operation takes place an imprint is made on the tab consisting of a black character immediately followed by a character in some other selected color or the reverse as may be desired.

A plurality of cards placed in the feeding mechanism and fed through the machine thus far described will be ejected from the rear end thereof properly cut and printed and arranged for positioning in a filing receptacle. As illustrated in Fig. 51, the cards 307 will have portions at their upper edges cut away, the first card passing through being imprinted with the character *xyz* and having its tab at the extreme right hand portion of the card the same as shown at 308 in Fig. 51. The last five cards of a pack cut and printed are shown in Fig. 51 and a tab 308 therein is the one that corresponds to the first tab of the entire pack cut and printed. Each tab will as it passes through the mechanism be imprinted with a character as shown at 309 and the other tabs 310 in each group of five cards will be stepped over toward the left, one step equal to one fifth of the width of a card as shown. This of course is what occurs when the staggered relation of the cards is in groups of five though, as previously noted, the staggered relation may be in groups of three or four or other desired number.

In addition to the above it is desirable when packs of index cards are made, to imprint on the body of the card the stock number of the card and either an advertisement of the one ordering the card or the name of the maker of the cards as shown at 311 and I have provided mechanism for accomplishing this before the cards are delivered to the receptacle placed at the end of the mechanism which finally received them after the operations of the mechanism are entirely completed. This mechanism consists of an auxiliary printing device at the end of the central section of the machine to which the cards are delivered from said central section. Before delivering to the auxiliary mechanism it is necessary that each card be stopped and held momentarily and then released to the mechanism at the proper time so that each imprint on the body of a card will be identical in position with that of every other card. A cam 312 is secured to the drive shaft 307. An arm 313 carries a roller 314 which bears against this cam, said arm being carried at the end of a shaft 324 mounted in a bearing on the support 315 which is secured to the horizontal beam 5. At its opposite end shaft 324 has a vertical arm 316 secured thereto with which is connected a horizontal link 317. A bar 318 is pivotally mounted at 319 beneath the table 23 extending to the rear and carrying at its rear end a substantially vertical stop member 320. A link 321 and a brace 321^a are interposed between bar 318 and the link 317 so that with each revolution of the cam 312 the stop 320 is carried above a rest 322 over which the cards pass as they are delivered from the table 23. It will be apparent that as the stop 320 is raised above this rest any card coming to it will be held from further movement during the time that the stop is elevated but that as soon as roller 314 is permitted to move inwardly toward the shaft 7 as it passes down over the shoulders of the cam 312 the stop will be lowered and the card permitted to pass on. A torsion spring 323 around the shaft 324, as shown in Fig. 8, exerts a tendency to hold the roller against cam 312 and stop 320 in its lowermost position.

On the drive shaft 7 is a sprocket wheel 325 driving the chain 326 which extends to the rear under the chain tightener 326^a and the sprocket wheel 327 fixed on shaft 328 and thence around sprocket wheel 329 fixed on the shaft 330. Shaft 328 is supported by and between sides 331 which form the main supports for the auxiliary printing mechanism and is carried in bearings 328^a which may slide up and down in slots formed in the supports 331. These supports in turn are carried by horizontal beams 332 which are positioned at the upper ends of vertical standards 333. The shaft 330 is of compara-

tively short length and has thereon a gear 334 meshing with gear 335 on the shaft 336 which extends between and is supported in suitable bearings in the supports 331. A 5 type carrying roller 337 is secured to the shaft 336 and has a plurality of T-shaped slots 338 in which type blocks may be secured.

The inking apparatus as a whole is located back of the type roll 337. It includes 10 a pair of spaced apart side members 339 between which are mounted a plurality of inking rolls. Roll 340 is mounted on shaft 341 which shaft at one end carries a pinion 341^a around which passes a chain 344 driven by the sprocket wheel 343 on shaft 336. Roll 344 is in contact with roll 340 and the printing roll 337 and is mounted on the 15 shaft 345 a distance above roll 340 being 20 adjustable with respect to said rolls to permit proper contact. Roll 346 is mounted on a shaft 347, the ends of which seat in the forked upper ends of substantially vertical arms 348, pivotally mounted on a 25 rod 349 which extends between the sides 339 and through the rear side. Arm 350 is secured at its rear end to this shaft, its front end being forked as shown at 351 to receive an eccentric 352 mounted upon the 30 shaft 336. It will be apparent with the rotation of shaft 336, that the forward end of arm 350 moves up and down in this manner operating the upper ends of arms 348 back and forth and intermittently bringing 35 roller 346 into contact with rolls 340 and similarly making intermittent contact with rolls 353 mounted back of rolls 346. Roll 353 is the roll against which the ink immediately engages as shown in Fig. 9 sliding 40 down the incline 354 which also serves as a scraper, its lower end bearing against the surface of roll 353. Said incline is attached to block 355 and adjustable thereon. Roll 353 is mounted on a shaft 356 which 45 extends through the rear side 339 and has at its end a ratchet wheel 357. A lever 358 is loosely mounted on the end of the shaft and carries a pawl 359 adapted to engage with the wheel so that as the lever is moved 50 in one direction the wheel is partially rotated. A second pawl 359^a engages with the ratchet wheel, this pawl being mounted on a handle 359^b which may be operated by hand to add more ink at times if the imprint 55 should become faint. A link 360 is pivotally connected to the lower end of lever 358 and extends forward therefrom being formed with a yoke 361 adjacent its forward end in which a second eccentric 352^a mounting 60 ed on shaft 336 is positioned, the effect being that when the eccentric rotates a back and forth movement is given to the link 360 thereby oscillating lever 358 back and forth to give step by step rotative movement to 65 the roller 353. Between its ends link 360

is formed with a slot 363 into which projects a pin 364 carried on the vertical shaft 365 which is mounted in bearings 365^a on the rear side 339 of the inking mechanism. Integrally formed with the shaft 365 is a 70 forked member 366, the forks passing above and below the shaft 341 and between disks 367 mounted thereon. This construction is shown fully in Fig. 12 and it will be apparent that when the machine is operating 75 the reciprocating movement given to link 360 causes a rocking of shaft 365 and a consequent back and forth oscillatory end-wise movement of the shaft 341 and the roll 340 mounted thereon so that the ink 80 transferred from roll 340 to roll 344 is spread smoothly and evenly over the last named roll.

A pressure roller 368 is mounted on and rotates with the shaft 328. The ends of 85 the roller 368 are recessed and in the recesses curved members 369 are positioned which at their lower ends are mounted on studs 370 projecting inwardly from the supports 331. Each of the members 369 90 carries a small roller 369^a on which the pressure roller 368 rides when said member 369 is in its upper position as shown in Fig. 9. It is held in upper position by a standard 371, one of these standards being 95 located at each end of the roller 368 and having a shoulder 372 at its upper end, the lower ends being pivotally mounted on a shaft 373 which extends between base members 374 connected to the supports 331. 100 Shoulders 372 are adapted to engage in notches 375 formed in the members 369. The recesses cut within the ends of the pressure roll 368 are of substantially circular outline except for a distance at the depression 377 as shown. When the members 369 are elevated and held on the shoulders 372 the pressure roller 368 and its shaft 328 together with its bearings 328^a are also elevated and the pressure roller runs entirely 105 on the rollers 369^a. When rollers 369^a are in the depressions 377 the pressure roller is lowered and does not bear against the printing roll 337 but as pressure roller 368 moves to another point and the rollers 369^a 110 are not in the depressions 377, the pressure roller is elevated and pressed against the type roller 337 exerting sufficient pressure 115 to cause an imprint upon a card that passes between them.

A link 378 is pivotally mounted at 379 between its ends on a support 378^a directly back of the central section of the machine and at its lower end carries a rearwardly projecting dog 380. There is also pivotally connected to the lower end of link 378 a second link 381 which is pivotally connected between its ends to the support 378^a and at its lower end it also carries a rearwardly projecting dog 382. These dogs at 120 125

their rear ends are connected by link 383 while a link 384 extends upwardly and to the rear, its upper end having pivotal connection with the lower end of an arm 385 5 secured to a shaft 386 which is mounted between the upwardly extending legs of a support 387. In the table 23 and very near the rear end thereof is formed an opening or depression 388, in which the curved end 10 of an arm 389 secured to the shaft 386 in substantially parallel relation with the arm 385 is adapted to seat as shown in Fig. 9. When it is thus seated the dogs are depressed and in their lowermost position as 15 shown in Fig. 9.

A support 390 is secured to the beam 332 and a rod 391 is slidably mounted at its upper end having one end provided with a head 392 formed with inclined sides 393 20 adapted to bear against a cam 394 fixed on the shaft 328. A coil spring 395 serves to press the head against the cam. The rod 391 at its end adjacent the dogs 380 and 382 is formed with a plurality of projections 25 396 on its upper and lower sides and when the parts are in the position shown in Fig. 9 the movement imparted to rod 391 as the cam 394 engages against head 392 causes a forward throw of the dog 380 and a turning 30 of the lever 378 about its pivot in this manner carrying link 397 which connects lever 378 with the member 371 to the rear and disengaging the shoulders 372 from the notches 375 permitting the curved members 35 369 to fall, thus lowering the bearings 328^a to their lowermost position so that pressure roller 368 and its shaft 328 will then turn in the bearings 328^a and be supported thereby without reference to the rollers 369^a and the 40 members 369 on which they are mounted. This occurs when no cards are passing through the machine and the effect, it will be apparent, is to lower the pressure roll so that it does not contact with the type roll 45 during this time when no operation of printing is necessary. As soon however, as cards begin to pass through the machine they pass under the end of member 389 elevating it and drawing the lower dog into position 50 such that it will be engaged by the projection 396 on the underside of rod 391, thereby exerting a forward pull on the link 397 and drawing the members 371 into position such that their shoulders 372 will engage in 55 the notches 375, it being evident that with each revolution of the shaft 328 cams 398 thereon engage on the undersides of the curved members 369 elevating them into proper position such that whenever the 60 members 371 are drawn forward the shoulders 372 may enter into the notches 375 after which the pressure roller will be carried entirely by the rollers 369^a and elevated with each revolution to press the card against 65 the type carried by the type roll 337. The

cards pass through the rollers and as finally completed drop into the receptacle 399 shown in Fig. 10. The first card printed with the last characters of the series is at the bottom and each card in reverse order of 70 the series as it comes to the receptacle will drop upon the card immediately preceding it. In this manner the cards will be stacked one above the other in proper order so that they may be removed from the receptacle in 75 packs fully printed, cut and stacked and ready for insertion in any suitable filing receptacle.

A pair of spaced apart vertical supports 400 are connected to the front guide 226 as 80 shown in Fig. 33 terminating at their upper ends in bearings 401. A plurality of ratchet wheels 402 are positioned between the bearings and mounted on the shaft 403 being spaced apart by collars 403^a. The 85 shaft extends a short distance in front of the front support 400 and has a disk 404 fixed thereon which near its periphery is provided with a projection 405. It is understood that one or more of these projections may be used. A plate 406 is slidably mounted in slots 407 formed on the inner sides of the supports 400 and links 408 are interposed between the plate and the lever extension 193 so that when the links are 90 connected to this extension and the machine is in operation, with each revolution of the main drive shaft 7, the plate is moved back and forth once in its guiding slots. A plurality of blocks 409, one for each ratchet 100 wheel, are secured to the upper side of the plate and pawls 410 projecting from supports 411 adjustably mounted in the blocks 409 are provided which may be engaged with the ratchet wheels, the parts 411 being 105 fixed in position with respect to the blocks on which they are mounted by set screws 412. In operation of the machine one of the pawls only is engaged with one of the ratchets serving in this manner to rotate the 110 shaft 403 step by step with the operation of the machine. These ratchet wheels are provided with different numbers of teeth to take care of different conditions with respect to number of cards in a pack, and the 115 like.

A bell crank lever 413 is pivotally mounted at 414 on the plate 175, one of its arms carrying a pin 415 which lies closely adjacent the disk 404 and in position such that 120 when the projection 405 comes opposite the pin it bears thereagainst turning the bell crank lever about its pivot. A link 416 is interposed between the end of the other arm of said bell crank lever and a member 417 125 pivotally mounted at 418 to a block 419 fastened on the front upper frame member 4 of the supporting frame, this member at its free end having a slot 420 through which projects a pin 421 on the T-shaped member 130

422, the head of which bears against the end of a lever 423 pivotally mounted between clips 424 fixed on the block 79 heretofore described. A coil spring 425 holds the end 5 of lever 423 in contact with the member 422 and at the opposite end a pin 426 projects from the lever through an opening in block 79 and into engagement with a notch 427 in the rod 80. As long as this pin is in 10 engagement with the notch rod 80 and block 79 move together, but when the projection 405 bears against pin 415 the operation of the bell crank lever 413 caused thereby, pulls link 416 to the rear operating member 417 15 about its pivot and forcing the T-shaped member 422 toward the block 79 and causing the disengagement of the pin from the notch and freeing the rod 80 from block 79, whereupon the feeding mechanism becomes 20 inoperative and no cards are fed into the machine as long as the engagement of projection 405 and pin 415 takes place. The remainder of the mechanism, may, however, operate and as soon as the projection 405 has 25 moved away from pin 415 the parts take their normal position and the feeding of the cards to the mechanism is resumed. In this manner there may be effected breaks in the continuous feeding of the cards to the 30 machine and this is of importance especially when the number of characters on the type rings is not exactly divisible by the number of tabs in staggered relation in a pack. In such cases there must at times be 35 lapses of one or two or more cards between the packs as each pack is completed in order to start the next succeeding pack with the properly positioned tab. Of course when each tab is equal in width to one-fifth 40 of a card the stopping of the feed is not necessary and the mechanism just described is not connected with the rest of the machine when packs of index cards of this character are made.

45 It is also desirable at times to render the printing mechanism for the tabs inoperative and in fact it is desirable that this be made automatically and follow closely any stopping of the feeding mechanism. Accordingly 50 I have provided a bar 428 which is pivoted at 429 to the forward guide 226 at its front end also carrying an upwardly projecting pin 430 which may be positioned for engagement by the projection 405 a short time 55 after this projection has engaged with the pin 415. Pin 430 is carried on a base 430^a which is adjustable with respect to the bar 429. The rear end of bar 429 engages with a lever 431 positioned vertical and pivotally 60 mounted between its ends on a bracket 432, its lower end terminating in a rounded head 433 which is received in a slot 434 in the bar 435, slidably mounted in U-shaped guides 436 that are secured on the under- 65 sides of the upper frame members 3 and 5.

A pair of spaced apart flat bars 437 are connected to the U-shaped member 222 extending backwardly and at their rear ends having pivotal connection to a link 438, the upper end of which is attached to the bar 70 435 and which is braced by braces 439 as shown in Fig. 33. At its rear end, bar 435 is attached to an upright lever 440 pivotally mounted between its ends to brackets 441.

A spring 442 normally draws bar 445 and 75 the mechanism attached thereto to the rear. The upper end of the lever 440 is forked and a pivotal connection made at 443 to a member 444 which is secured to the downwardly projecting end 445 of a sheet metal 80 element pivotally mounted between supports 446 and including a horizontal portion 447 to which is adjustably attached a member 448 which normally lies directly beneath the member 201 on push bar 199. 85

When the projection 405 engages pin 430 bar 428 is turned about its pivot and in consequence the lower end of lever 431 is operated forwardly sliding bar 435 in a forward direction and turning the U-shaped 90 member 222 about its pivot and to a position such that the roller 225 will not contact therewith while, simultaneously, plate 448 is elevated to lift the push bar 199 above pins 182. It is evident therefore that so 95 long as this projection is in engagement with pin 430 the type ring is stopped from movement and no upward movement of the post or ram 216 takes place, all tab printing operations being for a short time suspended. 100 This suspension of operation so far as printing the tabs is concerned takes place a short time after the suspension of the feeding operation and is timed so that the break in the feed of cards passing underneath the type 105 ring will occur simultaneously with the suspension of the printing operation. Of course a suspension of the feeding operation may take place without any following suspension of the printing operation by merely 110 adjusting the block 430^a so that its pin 430 will not be engaged by the projection 405. Similarly the plate 448 may be adjusted so that the type ring will continue movement though the printing ram is made inoperative. 115 In fact, practically any cut out of parts of the mechanism is possible to obtain through the various adjustments that are provided.

It is sometimes desirable to stop the printing operation while the feeding operation continues and I have provided means for manually effecting this. A lever 449 is pivoted at 450 having its rear end curved and extending back of the lever 431. A rod 451 is secured to the front end of lever 449 120 and extends forward to the front of the machine, its front end having connection with the lever 452 which is mounted on the bracket 453. By grasping the free end 454 of lever 452 it is possible to give a forward 125 130

sliding movement to bar 435 in this manner stopping all printing operation so far as the index tabs are concerned.

From the foregoing it will be apparent that I have provided a machine which will cut, print and stack index cards in packs and deliver them from the machine ready for insertion in any filing receptacle; that with this mechanism packs of cards with the tabs in staggered relation with two, three, four or five tabs for either the full width of a card or part of the width of a card may be produced; that indicating characters in ink of various colors may be imprinted on the tabs and that any desired advertisement, name of the manufacturer of the cards or the like may be imprinted upon the body of each card and in exactly the same position; that practically every feature of adjustment for the mechanism to successfully accomplish these results is incorporated in the machine and that with this machine practically any type or kind of index card or pack of index cards may be produced with or without index characters or advertisement thereon.

The construction described is of a complete and operative structure which has proven satisfactory in actual operation. It will be noted in this connection that the use of the machine and operation thereof has been described in connection with the cutting and printing of index cards and separators. It is to be understood that the machine is adapted to cut and print folders and like devices quite as well, the operation being the same in all respects. Of course many changes in structural features and detail may be resorted to without departing from the invention and I do not wish to be limited to the precise structure described but consider my invention to include all modifications of structure falling within the scope of the appended claims defining my invention.

I claim:

1. In a mechanism of the character described, a feeding mechanism for periodically delivering cards one at a time therefrom, a cutting mechanism operating periodically to cut the cards at one edge to leave an outwardly extending tab on each card, periodically operating printing mechanism in conjunction with the cutting and feeding mechanism for printing characters on the tabs, means to operate the feeding mechanism, the cutting mechanism, and the printing mechanism, and means to carry the cards from the feeding mechanism to the cutting mechanism and therefrom to the printing mechanism, substantially as described.

2. In a mechanism of the character described, a feeding mechanism for delivering cards therefrom one at a time, a carrying means on to which the cards are delivered, a

cutting mechanism to which the cards are carried, means to operate the cutting mechanism and feeding mechanism whereby a card is delivered from the feeding mechanism for each operation of the cutting mechanism, means to stop the cards at the cutting mechanism for operation thereon, substantially as described, a printing mechanism through which the carrying means operates to carry the cards thereto, and means to operate said mechanism as the cards are brought thereto.

3. In a mechanism of the character described, combined feeding, cutting and printing mechanisms, means to operate said mechanisms in conjunction with each other whereby cards may be delivered one at a time from the feeding mechanism, cut by the cutting mechanism, and printed by the printing mechanism in consecutive order, and means to carry the cards from the feeding to the cutting mechanism and therefrom to the printing mechanism, substantially as described.

4. In a mechanism of the character described, feeding, cutting and printing mechanisms, means to operate said mechanisms in conjunction with each other whereby cards may be delivered one at a time from the feeding mechanism, afterward cut one at a time by the cutting mechanism, and then printed by the printing mechanism, means to carry the cards from the feeding to the cutting mechanism and therefrom to the printing mechanism, means to stop the successive cards in different relative positions with respect to the cutting mechanism to thereby cut the consecutive cards differently and means to stop the cards after cutting in position for operation thereon by the printing mechanism, substantially as described.

5. In combination, feeding, cutting and printing mechanisms, means to operate said mechanisms in conjunction with each other whereby cards may be delivered one at a time from the feeding mechanism, afterward cut them one at a time by the cutting mechanism and then printed one at a time by the printing mechanism, means to carry the cards to the cutting mechanism and therefrom to the printing mechanism, knives on the cutting mechanism for cutting portions away from each card at one edge and leaving a projecting tab, means to stop each card during the operation thereon of the cutting knives and means to stop each card at the printing mechanism for printing on the tab left on said card, substantially as described.

6. In combination, feeding, cutting and printing mechanisms, means to operate said mechanisms in conjunction with each other to thereby deliver cards one at a time from the feeding mechanism, afterward cut them by the cutting mechanism and thereafter

- print them by the printing mechanism, co-acting knives included in the cutting mechanism for cutting the cards at one end to have a projecting tab on each card, means to stop successive cards at different positions with respect to the cutting mechanism to thereby locate the tabs on successive cards in different positions with respect to the bodies of the cards, means to carry the cards from the feeding to the cutting mechanism and then to the printing mechanism, and means to stop the cards for printing on said projecting tabs by the printing mechanism.
- 15 7. In combination, feeding, cutting and printing mechanisms, means to operate said mechanisms in conjunction with each other to deliver cards one at a time from the feeding mechanism, afterward cut them one at a time by the cutting mechanism and then print them one at a time, means to carry the cards from the feeding mechanism to the cutting and printing mechanism, co-acting knives included in the cutting mechanism for cutting the cards at one edge to leave a projecting tab on each card, a plurality of stops located adjacent the cutting mechanism, means to operate the stops in succession into the path of movement of the cards to stop them during operation of the cutting mechanism, and additional stops adjacent the printing mechanism operable in succession to stop the cards while the operation of the printing mechanism takes place.
- 20 8. In combination, feeding, cutting and printing mechanisms, means to operate said mechanisms in conjunction with each other to deliver cards one at a time from the feeding mechanism, afterward cut them one at a time by the cutting mechanism and print them one at a time by the printing mechanism, means to carry the cards from the feeding to the cutting and printing mechanisms, co-acting knives included in the cutting mechanism for cutting the cards at one edge to leave a projecting tab on each card, a plurality of stops located one behind the other and having their upper ends normally positioned below the path of movement of the cards, means for elevating the stops one at a time immediately before the operation of the cutting mechanism, a regulating stop in front of the plurality of stops, means to elevate said regulating stop into the path of movement of the cards to stop each card momentarily before it comes to the cutting mechanism, and means to stop the cards during operation of the printing mechanism, substantially as described.
- 25 9. In combination, a feeding mechanism having means to deliver cards one at a time therefrom, means to operate said mechanism, a conveying device to which said cards are delivered, a cutting mechanism including a stationary lower knife over which the
- cards are carried, a plurality of movable stops located back of said knife, means to elevate the stops successively into the path of movement of the cards to stop each card in position above said knife with successive 70 cards in different relative positions with respect to the knife, an upper relatively movable knife located above the lower knife, means to reciprocate the upper knife immediately after a card has been stopped, a 75 printing mechanism to which the cards are carried by the conveying device, means to operate said mechanism and means to stop each card with its tab in position for operation upon by said printing mechanism, substantially as described.
- 10 10. In combination, a supporting frame, a drive shaft mounted thereon, a table carried by the frame, a feeding mechanism positioned at the front end of the frame, means 80 for operating the feeding mechanism from the drive shaft to thereby deliver one card therefrom with each revolution of the shaft, an endless belt passing lengthwise over and under the table to which the cards are delivered, means for driving said belt continuously from the drive shaft, a cutting mechanism including stationary lower knives and movable upper knives in front of which the belt passes, means to lower and 85 raise the upper knives once with each revolution of the drive shaft, stop mechanism operated by the drive shaft for momentarily stopping the cards in position for action 90 of which the belt passes, means to lower and raise the upper knives once with each revolution of the drive shaft, stop mechanism operated by the drive shaft for momentarily stopping the cards in position for action 95 of which the belt passes, means to lower and raise the upper knives once with each revolution of the drive shaft, stop mechanism operated by the drive shaft for momentarily stopping the cards in position for action 100 of which the belt passes, substantially as described.
- 11 11. In combination, a supporting frame, a drive shaft mounted thereon, a table carried in front of the frame, a feeding mechanism positioned at the front end of the frame, means for operating the feeding 105 mechanism from the drive shaft to deliver one card with each revolution of the shaft, an endless belt passing lengthwise over and under the table receiving the cards, means for continuously driving the belt from the 110 drive shaft, yielding devices for forcing the cards into contact engagement with the belt, a cutting mechanism located adjacent the belt, means for operating the cutting mechanism once with each revolution of the drive 115 shaft, a plurality of movable stops normally located back of and slightly below the upper surface of the table, means to elevate one of said stops with each revolution of the drive shaft and to successively elevate all of the 120 stops with successive revolutions of said shaft to stop the cards in position for operation thereon by the cutting mechanism, a printing mechanism operated by the drive shaft through which the belt passes and 125
- 125 130

means to stop the cards at such mechanism for printing thereon.

12. In combination, a supporting frame, a table thereon, an endless belt passing lengthwise over and under the table adapted to carry cards or like articles thereon, a plurality of stops located one behind the other back of the table, blocks supported below the table for carrying the stops, a cam comprised of a plurality of spaced apart disks mounted for rotation on the frame, each disk having a projection thereon, means to rotate the cam, a plurality of pivotally mounted levers having ends engaging the disks and operable by the projections thereon and means interposed between the levers and stops for elevating a stop when its associated lever is operated, substantially as described.

13. In combination, a supporting frame, a table thereon, an endless belt passing lengthwise over and under the table adapted to carry cards or like articles thereon, a cutting mechanism adjacent the belt, a printing mechanism adjacent the belt and a distance from the cutting mechanism, means to operate the cutting and printing mechanisms, a plurality of stops back of and normally below the table located adjacent the cutting mechanism, similar stops adjacent the printing mechanism and means to elevate the stops into the path of movement of the cards to stop each card for operation thereon by the cutting and printing mechanisms, substantially as described.

14. In combination, a table, a conveying mechanism thereon, a feeding mechanism for feeding cards one at a time to the conveying mechanism, a cutting mechanism for cutting the cards and a printing mechanism for printing the cards located adjacent the conveying mechanism, a plurality of blocks supported under the table, a shaft in each block, a cam on the end of each shaft, a vertically positioned bar loosely carried by each block, each having a head at its upper end and a cam at its lower end contacting with the cam on its adjacent shaft, means normally holding said rods in lower position with the heads below the upper surface of the table, a cam having a plurality of spaced apart disks each with a projection thereon, levers pivotally mounted between their ends one for each disk and engaging with the disks, arms on the shafts in the blocks, rods interposed between the ends of said levers and arms, means to operate the feeding mechanism, cutting mechanism, conveying mechanism and printing mechanism and to rotate the cam, and means to stop the cards momentarily at the printing mechanism.

15. Stop mechanism for a machine of the character described, including a support, a plurality of blocks adjustably secured to the support, a shaft mounted in each block,

each having a cam at one end, a vertically positioned rod slidably mounted in each block and having its lower end resting on the cam, means to hold said rods in lower position, an arm secured to the opposite end of each shaft, a block pivotally connected to the end of each arm, rods one for each of the last mentioned blocks to which said blocks are adjustably connected, a composite cam comprised of a plurality of spaced apart disks each having a projecting portion mounted for rotation, a plurality of levers each having one end engaging a disk and the other end connected to a rod, said levers being pivotally mounted between their ends, and means to rotate the cam, substantially as described.

16. Stop and regulator mechanism including a plurality of vertically movable stops, a composite cam comprised of a plurality of disks, each having a projecting portion separated by intermediate disks provided with a plurality of projecting portions, means interposed between each stop and a disk for elevating said stop when the projection on the disk engages said means, a vertically movable regulator stop ahead of the plurality of stops, and means interposed between said regulator stop and an intermediate disk operated by said disk for elevating the regulator stop as a projection on the intermediate disk engages with the stop, the stop lowering when said means is between two projections.

17. Stop and regulator mechanism including a plurality of vertically movable stops, a composite cam comprised of a plurality of disks, each having a projecting portion separated by intermediate disks, each having a plurality of projecting portions, means interposed between each stop and a disk for elevating said stop when the projection on the disk engages said means, a vertically movable regulator stop located ahead of said plurality of stops, a member pivotally mounted adjacent the cam, a lever adjustably mounted on said member, a roller adjustably mounted on the lever and engaging an intermediate disk, an arm projecting from the member, a pivotally mounted bell-crank lever connected to the regulator stop, and a bar interposed between the bell-crank lever and said arm whereby the regulator stop is elevated when the roller rides over a projection on the intermediate disk, substantially as described.

18. Stop mechanism including a plurality of vertically movable stops, a second plurality of vertically movable stops located a distance back of the first stops, means for successively elevating the first stops one at a time, and connections between said first and second stops to cause the simultaneous elevation of a rear stop when a front stop is elevated.

19. In combination, a supporting frame, a table carried thereby, a cutting mechanism carried by the frame back of the table, an endless belt running lengthwise over and under the table, a feeding mechanism at the forward end of the table for delivering cards or the like one at a time to the belt, means to operate the feeding and cutting mechanism to deliver and to cut cards one at a time, means to continuously operate the belt, a printing mechanism back of the cutting mechanism, means to stop each card for operation thereon by the cutting mechanism, means simultaneously operable to stop the card previously cut by the cutting mechanism at the printing mechanism, and means to operate the printing mechanism, substantially as described. 70
20. In combination, feeding, conveying, cutting and printing mechanisms, means included in the feeding mechanism for delivering cards one at a time to the conveying mechanism, means to operate the feeding mechanism, means to operate the conveying mechanism to carry the cards to the cutting and the printing mechanisms, means to operate the cutting mechanism once with each card delivered by the feeding mechanism, means included in the cutting mechanism for cutting each card at one edge to leave a projecting tab, means for operating the printing mechanism once with each card delivered by the feeding mechanism, means to stop the cards for operation thereon by the cutting mechanism, and means to stop the cards for operation thereon by the printing mechanism to imprint on said tab, substantially as described. 80
21. In combination, feeding, cutting and conveying mechanisms, means to continuously operate the conveying mechanism, means to deliver cards or like articles one at a time to the conveying mechanism from the feeding mechanism, means included in the cutting mechanism for cutting each card at one edge to leave a projecting tab, means for operating the cutting mechanism, a type ring having a plurality of characters thereon, means to move the type ring one step with each card delivered to the conveying mechanism to change the position of the type, and means for pressing the tab of a card against the type on the ring, substantially as described. 90
22. In combination, feeding, cutting and conveying mechanisms, means to continuously operate the conveying mechanism, means to deliver cards or like articles one at a time from the feeding mechanism, said cards being carried to the cutting mechanism, means included in the cutting mechanism for cutting each card at one edge to have a projecting tab, means for operating the cutting mechanism once with each operation of the feeding mechanism, a type ring having a plurality of type characters thereon, said ring projecting over the conveying means, means to turn the type ring step by step to change the position of the type characters with each operation of the feeding and cutting mechanisms, means to force the tab of a card against the type character over the conveying mechanism, and means to stop the card during such operation. 95
23. In combination, feeding and cutting mechanisms, an endless belt leading from the feeding to the cutting mechanism, means to continuously operate the belt, means to operate the feeding mechanism to deliver cards or like articles one at a time to the belt, means included in the cutting mechanism for cutting each card at one edge to leave a projecting tab, means to operate the cutting mechanism, means to stop successive cards at the cutting mechanism at different positions to locate the tabs on successive cards differently, a type ring having a plurality of type characters on the underside thereof projecting at one point near the belt, means to turn the type ring step by step to change the position of the type characters in synchronism with the feeding and cutting mechanisms, means to force the tabs of the cards against the type characters, and means to momentarily stop each card so that its tab will lie directly beneath a type character during such operation. 100
24. In combination, feeding and cutting mechanisms, and an endless belt leading from the feeding to the cutting mechanism, means to continuously operate the belt, means to operate the feeding mechanism to deliver cards or like articles one at a time to the belt, means included in the cutting mechanism for cutting each card at one edge to leave a projecting tab, means for operating the cutting mechanism, means to stop the cards at the cutting mechanism at different positions to locate the tabs on successive cards differently, a type ring having a plurality of type characters on the underside thereof projecting at one point near the belt, means to turn the type ring step by step to change the position of the type characters in synchronism with the feeding and cutting mechanisms, a vertically movable ram over which the tabs of the cards pass, means to elevate said ram to press each tab against a type character, and means to stop each card with its tab above the ram during the printing operation. 110
25. In combination, a support, a type ring mounted thereon carrying a plurality of type characters on one face, a drive shaft, means to move the type ring step by step from the drive shaft, an inking device, means to raise the inking device into contact with a type character with each step in the movement of the ring, a movable ram having a head positioned at one side of the 125

ring, a cam on the drive shaft to engage with and move the ram toward the ring, an endless belt running adjacent the ram and ring, means to operate the belt continuously, 5 means to cut cards to leave a projecting tab at one edge located adjacent the belt, means to stop the cards for cutting and means to stop each card with its tab between the ram and a type character for printing, substantially as described.

26. In combination, a supporting frame, a type ring mounted thereon, a drive shaft, means to operate the type ring step by step from the drive shaft, a plurality of type 15 characters on the underside of the ring, a vertically movable ram mounted on the frame, a cam on the shaft against which the lower end of the ram seats, means holding the ram against the cam, an endless belt 20 continuously driven by the shaft to carry cards or the like above the cam and below the ring, a head extending over the ring above the ram, and stops to momentarily stop the cards carried by the belt for operation 25 thereon by the ram against a type character.

27. In combination, a supporting frame, a type ring movably mounted thereon, a drive shaft, a plurality of type characters 30 on the lower side of the ring, a plurality of pins projecting upwardly from the ring, a substantially horizontal lever pivotally mounted between its ends, one end extending over the type ring, a push bar pivotally 35 mounted on the end of the lever adjacent the pins, and means driven by the drive shaft to oscillate the lever back and forth to move the ring step by step with each revolution of the drive shaft.

40 28. In combination, a supporting frame, a plurality of brackets projecting upwardly therefrom carrying horizontal and vertical rollers, a type ring resting on the horizontal rollers and seated between the vertical 45 rollers, a plurality of pins projecting upwardly from the type ring, type characters attached on the underside of the ring, a substantially horizontal lever pivotally mounted between its ends and having one 50 end extending over the ring, a push bar pivotally secured to said end of the lever and adapted to engage against the pins, and means to oscillate said lever back and forth about its pivot to thereby rotate the type 55 ring step by step.

29. In combination, a supporting frame, a type ring horizontally positioned and mounted for rotation on the frame, a plurality of type characters mounted on the 60 underside of the ring, means for movably supporting the type characters permitting limited radial movements thereof, an inking device below the type rings including two sets of rollers adapted to engage with 65 the type to transfer two colors of ink, means

to engage with the support for the movable type to move it inwardly into position above one of the sets of rollers, means for engaging with and moving the type support outwardly, a vertically movable ram having a 70 head coming below the type ring, said head lying immediately below the type characters when in outer position, and means for elevating the ram, substantially as described.

30. In combination, a supporting frame, a 75 type ring horizontally positioned and mounted for rotation on the frame, a plurality of type characters fixed to the underside of the ring, a plurality of radially positioned guides secured to the underside of the 80 ring, slides in said guides, each slide having a type character at one end and a pin at the other end projecting downwardly therefrom, an inking apparatus having two sets of rollers, one located below the fixed type 85 characters and the other positioned inwardly therefrom, said rolls being adapted to receive differently colored inks, means to elevate said rollers, a stationary guide for receiving the pins on the slides to draw said 90 slides inwardly thereby hinging the type thereon above the inner set of rollers, a vertically movable ram carried by the frame, the ram having a head over which the fixed type characters pass, means located adjacent 95 said head to engage with the pins on the slides to force the type on the slides into position above the head of the ram, means to periodically elevate the ram, and means to rotate the type ring step by step between 100 elevations of the ram.

31. In combination, a feeding mechanism having means to deliver cards one at a time therefrom, a support back of the feeding mechanism, an endless belt mounted thereon, 105 means to operate the belt, means to operate the feeding mechanism to deliver the cards to the belt, a cutting mechanism positioned back of the table to which the cards are carried by the belt, means included in the cutting mechanism for cutting portions away at one edge of each card to leave a projecting tab, means to operate the cutting mechanism once with each card delivered to the belt, stops positioned one behind the other 110 adjacent the cutting mechanism, means to elevate the stops in succession to hold the cards for operation thereon by the cutting mechanism, means to render the feeding mechanism inoperative for a predetermined 115 period covering the time used in one or more operations of said feeding mechanism with the belt, cutting mechanisms and stops continuing their operations, a printing mechanism through which the belt passes, and 120 means to operate said mechanism to print on the tabs of said cards, substantially as described.

32. In combination, a feeding mechanism having means to deliver cards one at a time 125

- therefrom, a support back of the feeding mechanism, an endless belt mounted thereon, means to operate the belt, means to operate the feeding mechanism to deliver the cards 5 to the belt, a cutting mechanism positioned back of the table to which the cards are carried by the belt, means included in the cutting mechanism for cutting portions away at one edge of each card to leave a projecting tab, means to operate the cutting mechanism once with each card delivered to the belt, stops located adjacent the cutting mechanism, means to operate the stops in succession to stop the cards for operation 10 thereon by the cutting mechanism, means to render the feeding mechanism inoperative for a predetermined period covering the time used in one or more operations of the feeding mechanism, a type ring mounted on 15 the support, means to stop the cards with their tabs under type carried by the type ring, means to move the ring a step with each operation of the cutting mechanism, and means to render such means inoperative 20 25 after the feeding means have been rendered inoperative, substantially as described.
33. In combination, a support, a cutting mechanism thereon, means included in the cutting mechanism for cutting cards at one 30 of their edges to leave a projecting tab, an endless belt to carry the cards from the cutting mechanism, a type ring mounted on the support, means to move the ring a step governed by the distance between type on the 35 ring with each operation of the cutting mechanism, means to stop the cards with tabs thereof under a type character on the type ring, a vertically movable ram mounted on the support adapted to press the tabs 40 against the type characters, means to periodically elevate the ram once for each operation of the cutting mechanism, and means for rendering the ram operating mechanism, and the ring moving means inoperative for 45 a period of time covering one or more operations of the cutting mechanism with the belt, cutting mechanism, and stop means continuing their operations, substantially as described.
- 50 34. In combination, a support, a table mounted thereon, a cutting mechanism on the support having means for cutting cards to leave a tab on each card at one edge, a printing mechanism including a ring having 55 a plurality of type characters on the underside thereof mounted in the support, means to operate the cutting mechanism, means to move the ring step by step once for each operation of the cutting mechanism, a 60 vertically movable ram mounted on the support, means to carry cards from the cutting mechanism to the ram and ring, means to stop each card with its tab interposed between the ram and a type character on the 65 ring, a shaft rotatably mounted below the ram, a cam thereon engaging the ram to elevate it once for each operation of the cutting mechanism, a member pivotally connected to the ram with which the cam engages, means for moving said member away from the cam for a time covered by one or more operations of the cutting mechanism, and means simultaneously operated by said means for rendering the moving means for the type ring inoperative for an equal time, 70 75 substantially as described.
35. In combination, a support, a drive shaft mounted thereon, a type ring mounted on the support having a plurality of type characters on its underside and a corresponding plurality of pins projecting from its upper side, a lever pivotally mounted between its ends having one end extending over the ring, a push bar pivotally mounted at this end of the lever and resting on the 80 upper side of the ring, means for oscillating the lever about its pivot once with each revolution of the drive shaft, a vertically movable ram mounted on the support having a head positioned below one side of the ring, 85 means to elevate the ram once with each revolution of the shaft including a cam on the shaft with which a movable member on the ram engages, and means simultaneously operating to elevate the push bar above the 90 pins on the type ring and draw the movable member on the ram away from the cam, and means for operating said means for a period of time covered by one or more revolutions of the shaft.
36. In combination, a support, a type ring mounted thereon, a drive shaft, a plurality of pins projecting upwardly from the type ring, means including a push bar for engaging with the pins to operate the ring step by 95 step, one step with each revolution of the drive shaft, a ram carried by the support under one side of the type ring, a U-shaped member pivotally connected to the lower end of the ram, a cam on the drive shaft engaging said member to elevate the ram with each revolution of the drive shaft, a bar slidably mounted below the type ring, connections between it and the U-shaped member at one 100 end of the bar, means associated with the bar at the opposite end for raising the push bar above the said pins when the bar is moved in one direction, said movement simultaneously carrying the U-shaped member away from the cam, and means to move the bar, substantially as described.
37. In combination, a shaft, a ratchet wheel thereon, a disk secured to the shaft having a member projecting from its surface, a support carrying the shaft, a drive 105 shaft, means interposed between the drive shaft and ratchet wheel for moving the wheel one step with each rotation of the drive shaft, a feeding mechanism driven by the drive shaft having means to deliver cards 110 115 120 125 130

therefrom one at a time for each revolution of the drive shaft, a bell crank lever mounted adjacent the disk, a pin thereon interposed in the path of the projection on the disk, 5 means operated by movement of the bell crank lever to disconnect the feeding mechanism from the drive shaft, a printing mechanism including a type ring and a vertically movable ram under one side thereof, means 10 for moving the ring one step and for operating the ram upwardly once with each revolution of the drive shaft, a lever pivotally mounted adjacent the disk, a pin thereon located in the path of movement of the projection on the 15 disk, said pin positioned a predetermined distance back of the pin on the bell-crank lever, means interposed between said lever and the ram and ring operating means for rendering the ram and ring inoperative a 20 predetermined time after the feeding mechanism has been made inoperative, and cutting and conveying mechanisms driven by the drive shaft for cutting the cards between the feeding and printing mechanisms, and 25 for conveying the cards from the feeding to the cutting mechanism and from the latter to the printing mechanism.

38. In combination, feeding, cutting, conveying and printing mechanisms, means to 20 operate said mechanisms to deliver cards one at a time from the feeding to the conveying mechanism, whereby they are carried to the cutting mechanism, then to the printing mechanism and thereafter away from the 25 printing mechanism, means to stop the cards momentarily at the cutting mechanism for operation thereby, means to stop the cards momentarily at the printing mechanism for printing on the cards, an auxiliary printing 30 mechanism at the end of the conveying mechanism, adapted to print on the body of each card, means to momentarily stop each card before delivery to the auxiliary printing mechanism to thereby deliver each 35 card in the same relative position with respect to the auxiliary printing mechanism to thereby print upon each of the cards at the same position, and means to operate the stop, cutting mechanism, printing mechanism, 40 conveying mechanism and auxiliary printing mechanism, substantially as described.

39. In combination, means for cutting cards at one edge to leave each card with a projecting tab, with the tabs of successive 45 cards occupying different relative positions with respect to the bodies of the cards, means to print index characters on the tabs in consecutive order, conveying means for carrying the cards to and away from the cutting 50 and printing mechanisms, an auxiliary printing mechanism at the end of the conveying means to which the cards are delivered, means to stop the cards momentarily to cause each card to enter the auxiliary 55 printing mechanism at the same relative po-

sition of the parts thereof, and means operated by the cards for rendering the auxiliary printing mechanism operative, substantially as described.

40. In combination, a conveying mechanism 70 comprised of a table and an endless belt passing around the table, means to continuously drive the belt, a printing roll mounted at the end of the table, a pressure roll mounted below the printing roll, means for continuously driving said rolls, means for raising and lowering the pressure roll, and means interposed between the table and said raising and lowering means for controlling the latter to render it operative to raise the roll 75 when a card or like article is carried by the belt over the table, and lower the roll when no cards or the like are passing, substantially as described.

41. In combination, a printing roll mounted for rotation, a pressure roll positioned below the printing roll, a shaft on which the latter roll is secured, supports, bearings slidably mounted on said supports in which the shaft is mounted, flanges at each end of 80 the pressure roll, a member pivotally mounted within the recess made by said flanges at each end of the roll, rollers on said members, a table, a belt passing around the table, means for raising said members with each 85 revolution of the pressure roll shaft, means for holding the members in elevated position operated by the passage of articles carried by the belt over the table to the rolls, and means for continuously rotating the rolls. 100

42. In combination, an upper printing roll mounted for rotation, a pressure roll having recesses at each end located below the printing roll, a shaft on which the pressure roll is secured, bearings for the shaft, supports 105 in which the bearings are slidably mounted, a curved member with a notched end pivotally mounted within the recess at each end of the pressure roll, means for rotating the rolls continuously in opposite directions, a 110 cam on the shaft for elevating each member with the rotation of the shaft, rollers on the members adapted to engage the flanges of the pressure roll bounding said recesses when said members are elevated, uprights provided with shoulders adjacent the notched ends of said members, a shaft joining the lower ends of said uprights, a link secured at one end to one of the uprights, a lever pivotally mounted between its ends to which 120 the opposite end of the link is connected, a dog and a second lever pivoted to the opposite end of the first lever, said second lever being pivotally mounted between its ends, a second dog secured to the other end of 125 the second lever and extending in the same direction as the first dog, a link connecting the dogs, a bar slidably mounted adjacent the pressure roll shaft, a head thereon, a cam for operating the bar in one direction, 130

5 a spring forcing the head against the cam, projections on opposite sides of the bar adjacent the dogs to engage therewith, a table having a notch in its upper side, an arm pivotally mounted having a free end normally seating in the notch and means interposed between the arm and the dogs for elevating said dogs when the arm is raised out of the notch and lowering them when the arm seats in the notch, substantially as described.

10 43. In combination, a support, a table thereon, a belt passing around the table, a drive shaft mounted on the support continuously driving the belt, an auxiliary printing mechanism including upper and lower printing and pressure rolls at the end of the table, means to continuously rotate the rolls in opposite directions, one revolution for each revolution of the drive shaft, 15 a cam on the drive shaft, a stop pivotally mounted below the table at its end and normally positioned below the upper surface of the table, and means connected to said stop and operated by the cam once with each 20 revolution of the drive shaft to raise the stop above the upper surface of the table at its end and between it and the auxiliary printing mechanism, substantially as described.

25 44. In combination, a support, a type ring positioned horizontally and mounted for rotation on the support, means for rotating the ring step by step with intervals of rest between movements, a plurality of type characters on the underside of the ring, an inking mechanism positioned below the ring including a casing, a carriage mounted loosely within the casing, a plurality of inking rollers on the carriage, and means for momentarily elevating the carriage to bring the uppermost rollers therein into contact with a type character on the ring during the movement of said ring, substantially as described.

30 45. In combination, a support, a drive shaft mounted thereon, a type ring having a plurality of type characters on its underside positioned horizontally and mounted for rotation on the support, means for moving the type ring step by step, one step at a time interposed between the ring and drive shaft, an inking mechanism positioned below the ring including a casing, a carriage mounted loosely within the casing, upper idle rollers carried by the carriage, a roller located below said idle rollers and continuously driven by the drive shaft, means to give said last mentioned roller lengthwise oscillatory movements, means for transferring ink to said last mentioned roller, and means driven by the drive shaft for periodically elevating the carriage to bring the upper idle rollers in contact with the type characters on the rings, substantially as described.

35 46. In combination, a support, a drive shaft mounted thereon, a type ring posi-

tioned horizontally and mounted for rotation on the support, means interposed between the drive shaft and type ring for rotating said ring step by step one revolution with each revolution of the shaft, a plurality of type characters on the underside of the ring, an inking mechanism positioned below the ring at one side comprising a casing, a roller mounted between the sides of the casing against which ink contacts, means 70 to give said roller step by step rotation, a carriage movably mounted between the sides of the casing, a lower idle roller normally contacting with the first mentioned roller when the carriage is in lowermost position, a second roller mounted between the sides of the casing, means for continuously driving said second roller from the drive shaft, a pair of idle rollers mounted at the upper part of the carriage and normally contacting with said 75 last mentioned roller, and means for elevating the carriage once with each revolution of the drive shaft driven by the drive shaft to bring the upper idle rollers into contact with the type characters on the ring, substantially as described.

80 47. In combination, a support, a drive shaft mounted thereon, a type ring positioned horizontally mounted for rotation upon the support, means interposed between 95 the drive shaft and type ring for moving it step by step one step with each revolution of the drive shaft, a plurality of type characters on the underside of the ring, an inking mechanism positioned below the ring including a casing having spaced apart sides, a roller mounted between the sides of the casing, inclines mounted between the sides of the casing down which the ink moves against said roller, means for turning said roller 100 driven by the drive shaft, a second roller mounted between the sides of the casing continuously driven by the drive shaft, a carriage movably mounted between the sides of the casing, an idle roller carried by the carriage interposed between the two rollers mounted between the sides of the casing and normally contacting with the first of said rollers when the carriage is in lowermost position, upper idle rollers mounted on the 105 carriage normally contacting with the second mentioned roller mounted between the side of the casing when the carriage is in lowermost position, means to give a lengthwise back and forth oscillatory movement 110 to said last mentioned roller, and means to periodically elevate the carriage once with each revolution of the drive shaft to bring the idle rollers at the upper side of the carriage into contact with the type characters, substantially as described.

115 48. In combination, a support, a drive shaft mounted thereon, an inking apparatus mounted on the support comprised of a casing having spaced apart sides, a bar slidably 120

125 130

mounted on one side of the casing, means to move the bar back and forth, a shaft mounted between the sides of the casing, a roller on the shaft, a lever connected to the 5 shaft and fastened to said bar, a ratchet wheel on the shaft, a pawl on the lever engaging with the ratchet wheel, a carriage mounted between the sides of the casing, a lever pivotally mounted to the base of the 10 casing on which the carriage rests, a shaft located between the sides of the casing, a member on said shaft bearing on the free end of the lever, a bar pivotally mounted between its ends on the side of the casing, a 15 block pivotally mounted at one end of the lever, a pin projecting downwardly from the block, spring means tending to hold the block underneath the lever, a block having a downwardly inclined front portion secured 20 to the first mentioned bar adjacent the pin, said block having its opposite end inclined inwardly toward the side of the casing, connections between the last mentioned shaft and lever for turning the shaft on operation 25 of the lever to thereby elevate the carriage, a third shaft mounted between the sides of the casing, a roller on said shaft, means to

rotate said shaft continuously from the drive shaft, idle rollers mounted on the carriage between the first and last mentioned 30 rollers, and above the last mentioned roller, a type ring mounted for rotation on the support above the carriage, and means to move the type ring one step with each revolution of the drive shaft, substantially as described. 35

49. A mechanism of the character described including means for cutting, means for printing and means for stacking index cards or the like with the tabs of the cards in staggered relation one behind the other, substantially as described. 40

50. A mechanism of the character described including means for consecutively cutting index cards to leave a tab at one edge of each card, said tabs on the successive 45 cards being differently positioned with reference to the said edges of said cards, means for successively printing index characters on said tabs, different characters being printed on successive tabs, and means to deliver the 50 cut and printed cards from the machine, substantially as described.

In testimony whereof I affix my signature.
ISAAC WAGEMAKER.
